POWER OPERATED WOOD PLANE WITH CHIP AND SHAVING DISCHARGE MEANS

Arthur N. Emmons, Nedrow, N. Y., assignor to The Porter-Cable Machine Company, Syracuse, N. Y., a corporation of New York

Application March 15, 1955, Serial No. 494,353

8 Claims. (Cl. 145—4)

This invention relates to power operated wood planes. Planes of this type include a frame to which an electric motor is attached and which provides the power for rotating, at a high speed, a suitable cutter exposed through the bottom side of the plane for contact with the work being finished. The motor provides the power for the cutting operation whereby the energy expended by the operator is essentially only that necessary to guide the tool and accordingly, these planes are used extensively by carpenters, especially in work on the interior trim of buildings, such as fitting and hanging doors, sash, etc.

Because of the high speed power operated cutter and the rapid movement with which the operator can conveniently move the plane, a relatively large amount of material may be removed from the work piece by one pass of the plane. This results in the rapid production of a large quantity of shavings and chips, or splinters, which must be removed from within the frame housing of the plane—otherwise the shavings, and especially the splinters, have a tendency to pass under the cutter and, when they do so, the surface being finished is rendered defective.

This invention has as an object a portable, power-operated, plane embodying a structural arrangement which functions to effectively discharge the shavings and splinters removed from the work piece by the cutter in a manner to prevent the shavings and chips from being directed between the cutter and the surface being finished.

The invention has as a further object structural improvements in this type of plane which will be referred to in greater detail hereinafter.

The invention consists of the novel features and of the combinations and constructions hereinafter set forth and claimed.

In describing this invention, reference is had to the accompanying drawings in which like characters designate corresponding parts in all the views.

In the drawings—

Figure 1 is a top plan view of a power plane embodying my invention with parts broken away and parts in section;

Figure 2 is an end elevational view looking to the left in reference to Figure 1;

Figure 3 is a bottom plan view;

Figure 4 is a side elevational view looking to the right, Figure 2, with parts removed and parts in section;

Figure 5 is a view taken on line 5—5, Figure 2;

Figure 6 is a sectional view of the frame body taken on line 6—6, Figure 5;

Figure 7 is a view taken on line 7—7, Figure 4;

Figure 8 is a view taken on line 8—8, Figure 5; and Figure 9 is a view taken on line 9—9, Figure 7.

The structural arrangement of the plane in general consists of an elongated cast metal frame formed at its forward end with a body portion and a rearwardly extending shoe portion which engages the finished surface of the work piece. The body is provided with a handle for manipulating the tool, an electric motor mounted on the

2

rear side of the frame and having its shaft extending through a cutter chamber formed in the body portion of the frame. A depth adjustment shoe is mounted on the forward end of the body portion for adjustment toward and from the plane of the main shoe portion of the frame, the adjustment of this forward shoe determining the amount of material removed from the work piece in one pass of the plane. The body portion of the frame is also provided with a chip compartment arranged forwardly of the cutter compartment and having communication therewith so that any large chips or splinters removed from the work piece by the cutter will be discharged into this chip compartment.

The body portion of the frame is indicated at 10, and the frame is formed with a rearwardly extending shoe portion 11, the under or bottom surface 12 of which is machined smooth for sliding engagement with the surface being planed. The frame is provided with a split handle one-half of which, as shown in Figure 4, is formed integral with the frame and has a portion 13 inclining forwardly and upwardly and merging with the forwardly and downwardly inclining portion 14 joining the top wall of the body portion 10. The handle is completed by a mating section 16 secured to the integral handle portion 13—14 by screws 17 threading into bosses 18 formed in the integral portion of the handle. These mating sections form a hollow handle portion in which the motor switch 20 is positioned, and which is actuated by a trigger member 21. Power is supplied to the motor, mounted in the housing 22, through a cord 23 provided with a grip member 24 fixedly secured in the rear lower portion of the handle, see Figure 4.

The body portion of the frame is formed with a cutter compartment 25 and a chip compartment 26, these compartments extending transversely of the frame and being separated by a partition rib 27, see Figures 3, 5 and 8. A depth adjustment shoe 30 is mounted on the forward end wall 31 of the chip compartment 26. The shoe 30 is formed with a vertical wall 32 and a forwardly extending horizontal portion 33. A reinforcing rib 34 is provided at each side of the shoe. The vertical wall portion 32 is formed with a slot 35 to slidably receive the heads of the pins 36 mounted in the front wall 31 of the frame. The shoe is adjusted vertically on the pins 36 by a cam member 37 rotatably mounted upon a stud screw 38 threaded into the wall 31, and secured by a jam nut 39, see Figure 4. The cam member 37 is provided with a knob having an arm portion 40 to effect convenient rotation of the cam on the stud 38. The shoe has a rearwardly extending portion in the form of a plate 42 affixed to the shoe as by screws 43. This plate extends rearwardly and forms a bottom wall for the chip compartment 26, and terminates substantially in registration with the lower edge of the partition member 27, the partition member terminating short of the plate 42 to provide a passage 45, see Figure 4, for the discharge of chips and splinters removed from the work piece by the cutter 46, which is rotated in a counterclockwise direction, Figure 5.

The chip compartment 26 is formed at its inner end with a wall structure 50 formed with an aperture 51. The partition member 27 extends transversely of the frame in substantially parallel relation to the cutter 46. The top wall 54 and the side wall 55 of the cutter compartment are curved to form a substantially conical surface, see Figures 5, 7 and 8. The side wall 55 is curved forwardly, as at 56, and merges with a rib 57 extending transversely of the cutter compartment. As previously stated, the cutter 46 rotates in a counter-clockwise direction, Figure 5, and the blades of the cutter are of spiral formation, see Figure 3. The conical formation of the chip compartment, in conjunction with the spiral cutter, serves to effect discharge of the shavings produced from

the cutter outwardly through the open end of the compartment 25.

The motor housing 22 includes an intermediate casting 58. The intermediate section 58 is secured to the main portion of the housing 22 by screws arranged in apertures 59 formed in the intermediate member and threading into the main portion of the housing 22. The intermediate member 58 is attached to the rear side of the frame by a stud 60 fixedly secured in the aperture 61, see Figures 1 and 9. The stud 60 is journaled in an aperture formed in the inner end wall 50 of the chip compartment and is secured thereto as by nut 62. The intermediate member is also formed with a rearwardly extending arm 64 formed with a rectangular slot 65. A rectangular block 66 is slidably mounted in the aperture 65 of the arm and is provided with a circular bore to receive a cam portion 67 formed on a stud 68 journaled in the frame and secured by a nut 70. The outer end of the stud is formed with a handle portion 71 to effect convenient rotation of the cam 67. With this arrangement, the motor housing is moved vertically about the pivot 60 to provide adjustment so that the outer edges of the cutter blades are positioned in the plane of the bottom surface 12 of the rear supporting shoe. The armature shaft 73 of the motor is journaled in an anti-friction bearing 74 mounted in the intermediate member 58, the shaft extending through the bearing and forming an arbor on which the cutter 46 is detachably secured as by a nut 75. A fan 77 is fixed to the armature shaft within the intermediate member 58 and functions to effect air flow axially through the motor and which is discharged through apertures 78 formed in the bottom portion of the inclined wall surface 80 of the member 58, see Figures 3 and 9. The intermediate member 58 is also formed with an aperture 81 which is positioned in registration with the aperture 51 formed in the end wall 50 of the chip compartment. In order to provide a heavy air blast for discharging through the apertures 81, 51, the member 58 is formed with a rib portion 82, see Figure 9. In reference to Figure 9, the armature shaft 73 rotates in a clockwise direction, the rib 82 extending toward the fan and thus providing a partition member to effect discharge of the air set in motion through the aperture 81.

In the operation of the plane, any large chips or splinters are discharged by the cutter through the passage 45, Figure 5, into the chip compartment and the strong air blast through the aperture 51 effects outward discharge of such chips.

A closure member 85 is detachably secured to the body 10, as by screws 86. This closure member is formed with a vertical outer wall portion 87 spaced outwardly from the contiguous side of the frame and overlying the upper portions of the cutter and chip compartments 25, 26. This outer wall portion 87 is formed with a depending portion 88 positioned in registration with the cutter 46 to provide a guard therefor. The depending portion 88 is appreciably shorter in length than the main wall 87 of the closure, with its ends terminating in spaced relation to the side wall 55 of the cutter compartment and the front end wall 31 of the chip compartment, thereby providing ample space for the discharge of shavings and chips from these compartments and yet serves to effectively guard the cutter. The closure member is formed with a rib 90 forming a continuation of the partition 27, see Figure 3.

The rear portion of the top wall 92 of the supporting shoe 11 is formed with an upwardly extending projection 93 of somewhat conical formation and arranged midway between the side edges of the frame and being spaced rearwardly from the handle where the cord 23 enters the same. This projection 93 is employed to maintain the cord in angular relation to the axis of the frame. That is, the cord or the grip portion 24 thereof is positioned on one side of the other of the projection 75

93, causing the cord to extend outwardly from the handle portion in angular relation to the frame of the plane. The cord may be flexed to be positioned on either side of the projection 93, see Figure 1. This arrangement prevents the cord from extending rearwardly over the work being planed, in which position the cord has a tendency to catch on the edge of the door or work piece over which the plane was initially moved in the commencement of the cut or planing operation.

The intermediate motor housing section 58 is formed with an aperture 94 in the upper portion thereof and which is arranged in registration with an aperture 95 formed in the body section 10 and which communicates with the interior of the handle structure. These apertures provide a passage for wires 96, 97, extending to the motor. With this arrangement, all wiring is enclosed.

The plane is provided with the conventional guide plate 98 provided with brackets 99 mounted on pivot pins 100 carried by brackets 101 secured to the rear side of the frame, as by screws 102. This arrangement permits angular adjustment of the guide plate 98, as will be well understood. The brackets 99, 101, are clamped together in adjusted position by wing nuts 104.

What I claim is:

1. A portable power-operated wood plane comprising a frame formed at its forward end with a body portion and having a supporting shoe portion extending rearwardly from said body portion, said body portion being formed with a cutter compartment and a separate chip compartment located forward of said cutter compartment, the lower portions of said compartments being in communication, said compartments extending transversely of the frame and being open at like ends for the discharge of shavings and chips therefrom, said cutter compartment having an opening in the bottom wall thereof, a motor mounted on the frame at the ends of said compartments opposite to said like ends and having a power shaft extending into said cutter compartment, a cutter mounted on said shaft and being exposed through the opening in the bottom wall of said cutter compartment, and a depth adjustment shoe mounted at the forward end of said body portion for movement vertically toward and from the plane of said supporting shoe.

2. A portable power-operated wood plane comprising a frame formed at its forward end with a body portion and having a supporting shoe portion extending rearwardly from said body portion, said body portion being formed with a cutter compartment and a chip compartment arranged in adjacency thereto and being separated from said cutter compartment by a substantially vertically disposed partition member, the lower edge of said partition member terminating in spaced relation to the plane of said supporting shoe, said compartments extending transversely of the frame and being open at like ends for the discharge of shavings and chips therefrom, said cutter compartment having an opening in the bottom wall thereof, a motor housing mounted on the frame at the ends of said compartments opposite to said like ends and extending outwardly from the body portion of the frame, a motor mounted in said housing and having a power shaft extending into said cutter compartment, a cutter mounted on said shaft and being exposed through the opening in the bottom wall of said cutter compartment, and a depth adjustment shoe mounted at the forward end of said body portion for movement vertically toward and from the plane of said supporting shoe.

3. A portable power-operated wood plane comprising a frame formed at its forward end with a body portion and having a supporting shoe portion extending rearwardly from said body portion, said body portion being formed with a cutter compartment and a chip compartment, said compartments extending transversely of the frame and being separated by a partition member arranged in spaced relation upwardly from the plane of said supporting shoe, said compartments being open at like ends at one side of

the frame for the discharge of shavings and chips, a motor housing mounted on the opposite side of the frame and extending outwardly from the body portion thereof, a motor mounted in said housing and having a power shaft extending into said chip compartment, said housing being adjustable toward and from the plane of said supporting shoe, said chip compartment being formed with an opening in the bottom wall thereof, a cutter mounted on said shaft and being exposed to the opening in the bottom wall of the cutter compartment for engagement with the surface being planed, and a depth adjustment shoe mounted at the forward end of said body portion for movement vertically toward and from the plane of said supporting shoe.

4. A portable power-operated wood plane comprising a frame formed at its forward end with a body portion and having a supporting shoe portion extending rearwardly from said body portion, said body portion being formed with a cutter compartment having top, rear and bottom walls, and a chip compartment located forward of said cutter compartment, said compartments extending transversely of the frame and being separated by a partition member forming the forward wall of the cutter compartment, said compartments being open at like ends at one side of the frame, a motor mounted on the frame at the ends of said compartments opposite to said like ends and having a power shaft extending into said cutter compartment, the bottom wall of said cutter compartment being formed with an upstanding ridge spaced rearwardly from said partition, the top, rear and bottom walls of said cutter compartment being of substantially conical formation diverging toward the open end of the compartment, a cutter fixedly mounted on said shaft in the cutter compartment and being positioned for rotation thereby between said ridge and said partition, the lower edge of said partition terminating in spaced relation to the plane of said supporting shoe, and a depth adjustment shoe mounted at the forward end of said body portion for movement vertically toward and from the plane of said supporting shoe.

5. A portable power-operated wood plane as defined in claim 3 and including cam means carried by the body and operable to effect adjustment of said motor housing toward and from the plane of said supporting shoe.

6. A portable power-operated wood plane as defined in claim 3 including cam means carried by the frame and operative to adjust said motor housing and said depth adjustment shoe toward and from the plane of said supporting shoe.

7. A portable power-operated wood plane comprising a frame including a body portion and a supporting shoe portion extending rearwardly from said body portion, said body portion of the frame being formed with a cutter compartment and a separate chip compartment located forwardly of said cutter compartment, said compartments

extending transversely of the frame and being open at one side thereof for the discharge of shavings and chips from said compartments, a motor mounted on the opposite side of the frame from said compartments and having a power shaft extending into said cutter compartment, a cutter mounted on said shaft for rotation thereby in said cutter compartment, said chip compartment having communication with said cutter compartment, and the end wall of said chip compartment adjacent said motor being formed with an aperture, the end wall of said motor housing contiguous to the end wall of said chip compartment being formed with an opening in registration with said aperture, a fan mounted on said shaft and operable to discharge an air blast through said aperture toward the open end of said chip compartment, and a depth adjustment shoe mounted on the forward end of said body portion for movement toward and from the plane of said supporting shoe.

8. A portable power-operated wood plane comprising
20 a frame formed at its forward end with a body portion
and having a supporting shoe portion extending rear-
wardly from said body portion, said body portion being
formed with a cutter compartment having top, rear and
25 bottom walls, and a separate chip compartment positioned
immediately forward of said cutter compartment and hav-
ing communication therewith, said compartments being
open at like ends, the top and rear wall portions of said
cutter compartment being curved and diverging toward
30 the open end of the compartment to provide a substan-
tially conical formation, said chip compartment includ-
ing a closed end wall formed with an aperture, a motor
housing mounted on the frame at the ends of said com-
partments opposite to said like ends and extending out-
35 wardly from the body portion of the frame, a motor
mounted in said housing and having a power shaft ex-
tending into said cutter compartment, the bottom wall
of said cutter compartment being formed with an open-
ing, said motor housing having an aperture positioned
40 in registration with said opening in said chip compart-
ment, a cutter mounted on said shaft and being exposed
through said cutter compartment opening, a fan mounted
on said shaft in said motor housing and being operable
to discharge an air blast through said chip compart-
45 ment aperture and motor housing opening to effect discharge
of chips from said chip compartment, and a depth adjust-
ment shoe mounted at the forward end of said body por-
tion for movement vertically toward and from the plane
of said supporting shoe.
